(57) **CLAIM**

I claim the ornamental design for a shower rod bracket, as
shown and described.

DESCRIPTION

FIG. 1 is a perspective view of a shower rod bracket
embodying the present invention.

FIG. 2 is a front view of the shower rod bracket shown in
FIG. 1.

FIG. 3 is a left side view of the shower rod bracket shown
in FIG. 1.

FIG. 4 is a right side view of the shower rod bracket shown
in FIG. 1.

FIG. 5 is a top view of the shower rod bracket shown in FIG.
1; and,

FIG. 6 is a bottom view of the shower rod bracket shown in
FIG. 1.

The broken lines immediately adjacent the shaded areas
represent the bounds of the claim and all other broken lines
are for illustrative purposes only. None of the broken lines
form part of the claimed design.
